UNITED STATES PATENT OFFICE.

ODILON BOIVIN, OF MONTREAL, QUEBEC, CANADA.

APPARATUS FOR FORMING RIBS ON INSOLES.

Application filed October 6, 1923. Serial No. 667,027.

To all whom it may concern:

Be it known that I, ODILON BOIVIN, a subject of the King of Great Britain, residing at Montreal, Province of Quebec, Canada, have invented certain new and useful Improvements in Apparatus for Forming Ribs on Insoles; and I do hereby declare that the following is a full, clear, and exact description of the invention, such as will enable others skilled in the art to which it appertains to make and use the same.

The present invention pertains to novel improvements in an apparatus and method for forming ribs on insoles to be used in shoes.

The process hitherto employed consists in carving out a portion of the insole blank at the bottom thereof in such a manner as to leave a protruding rib. Such an operation requires considerable work and is known to be expensive in practice.

One of the principal objects of this invention is the provision of a machine whereby the operation may be performed at less expense. The machine is in the nature of a punch comprising a bed and a movable or punch carrying member. The bed is so constructed that certain parts thereof may be positioned and clamped together to form a groove therein. The movable member carries a bent presser plate having the contour of the rib to be formed and designed to enter the groove. This plate is held in place by locks and clamps similar to those employed on the bed. Several sets of such blocks may be provided for accommodating presser plates of desired sizes and shapes. The blank insole on which a rib is to be formed is laid upon the bed, and the movable member is actuated so that the presser plate enters the groove as far as possible, carrying with it a strip of the insole. There is thus formed a rib around the insole having the shape of the groove and presser plate.

This rib is made permanent by stitching passed through the sides thereof. This process, employed in connection with a machine, constitutes a further object of the invention.

The invention is fully disclosed in the following description and in the accompanying drawings in which:

Figure 1 is a bottom plan view of the punch carrying member;

Figure 2 is a vertical section through the apparatus, showing the punch carrying member and table; 55

Figure 3 is a detail showing an alternative set of blocks;

Figures 4, 5 and 6 are similar detail sections showing the relation of parts at various stages of the process; 60

Figure 7 is an elevation of a machine for stitching the rib;

Figure 8 is a perspective view of an insole having a rib formed around the toe and at 65 the shank;

Figure 9 is a perspective view of an insole of a child's shoe having a rib formed around the entire periphery; and,

Figure 10 is a cross section of a completed 70 ribbed insole.

Reference will now be had to these views by means of like characters which are employed to designate corresponding parts throughout. 75

The numeral 1 indicates in general a table which is in the nature of a stationary bed plate of a punch machine. On the top of this member is formed a pair of lateral flanges 2 through which set screws 3 are 80 threaded.

The movable or punch carrying member 4 is formed with similar flanges 5 through which are passed set screws 6. The central portion of this member is adapted to carry 85 an inside wooden block 7 supported by means of pins 8. This block is made of wood and has the configuration of the rib to be formed on the insole. It is adapted to be engaged around its periphery by a punch or presser plate 9. This may entirely surround the inside block for forming a rib of the type shown in Figure 9, or may surround it partially for stamping a rib of the character shown in Figure 8. Against 90 the plate 9 are placed a plurality of retaining wooden blocks 10 suitably cut for fitting tightly against the plate. The lateral blocks 10 are engaged by longitudinal clamping wooden blocks 11. Between these are disposed similar wooden clamping blocks 14 adapted to bear against the end retaining blocks 15. The ends of the blocks 14 are formed with slots 12 having a substantially oval cross section. Threaded bolts 13 are 105 passed through the ends of blocks 11 and

through slots 12 in such a manner as to connect the outer blocks and clamp them against the inner blocks. It will be observed that the bolts are of the usual circular cross section

5 so that the blocks 14 are allowed a small amount of play by the slots 12. The members 14 are engaged by the set screws 6 whereby they may be tightly pressed against the members 15.

10 The table 1 similarly carries an inside block 7' having the same contour as the member 7 but of a slightly smaller area. Around this block is placed a leather spacer 16 which in turn is surrounded by a boundary plate 17 whereby there is formed a peripheral space 18 around the member 7'. This space is adapted to receive the presser plate 9, as pointed out below. The boundary plate is held in tight engagement with the washer by means of clamp blocks 11' and 14', the latter being actuated by the set screws 3. The construction of the blocks 11' and 14' is such as to accommodate bolts 13' and other actuating mechanism similar 25 to that described with reference to Figure 1.

The form of the invention already described is adapted to contain a closed presser plate for forming a rib entirely around the periphery of the insole as illustrated in Figure 9. In Figure 3 is illustrated an alternate set of blocks for holding a presser plate 9' for forming a partial rib of the character shown in Figure 8.

In the operation of the invention as thus 35 far described, the desired presser plate is clamped into position by means of the blocks, bolts and set screws, as will be obvious from the description of Figures 1 and 2. The insole 18' is now placed upon the 40 lower inside block 7' while the member 4 and associated parts are spaced therefrom as shown in Figure 4. The movable member 7 is now pressed downwardly, whereby the plate enters the space 18, carrying with it a 45 corresponding portion of the insole. The member 4 is moved downwardly until the plate reaches its limit on the bottom of the

space 18, forming the stamped rib designated by the numeral 19 in Figure 6. The punch carrying member 4 is now raised and 50 the insole is removed.

The process is completed by stitching the rib thus formed. This operation consists in placing one side of the rib upon the table 20 of the sewing machine, as shown in Figure 7. The base of the insole bears against a guide roller 21 while the needle 22 is caused to pass through the rib from the opposite or inner side thereof. The insole is turned until the entire rib is stitched, as 60 shown in cross section in Figure 10.

It will be obvious that the member 1 may be movable while the member 4 is stationary, or that both members may be movable if 65 conditions require such a construction.

While a specific embodiment of the invention has been illustrated and described, it is to be understood that various alterations in the details of construction may be made without departing from the spirit of the invention as indicated by the appended claim. 70

Having thus fully described the invention, what I claim as new and desire to protect by Letters Patent is:—

An apparatus for making insole ribs comprising a bed, an inside block secured thereto, a spacer surrounding said block, a boundary plate surrounding said spacer and forming a groove with the block, retaining blocks engaging said boundary plate, clamping blocks engaging said retaining blocks, screws for pressing said clamping blocks into engagement with the retaining blocks, a punch carrying member movable relatively to said bed, an inside block carried by said member, a presser plate engaging the periphery of said block and adapted to enter said groove, retaining blocks engaging said plate, clamping blocks engaging said retaining blocks, and screws for pressing said clamping blocks into engagement with the retaining blocks. 75 80 85 90

In witness whereof I have hereunto set my hand.

ODILON BOIVIN.
